United States Patent Office

Des. 180,954
Patented Sept. 10, 1957

180,954

PLATE OR SIMILAR ARTICLE

Ann F. Landau, Beverly Hills, Calif., assignor to Wallace China Co., Ltd., Los Angeles, Calif., a corporation of California

Application October 22, 1956, Serial No. 43,463

Term of patent 14 years

(Cl. D44—15)

The figure is a face view of a plate or similar article, showing my new design.

The plate is of a conventional configuration when viewed from the side thereof.

I claim:

The ornamental design for a plate or similar article, substantially as shown and described.
